(57) **CLAIM**

The ornamental design for a vehicle, toy replica and/or other replicas, as shown and described.

DESCRIPTION

This application contains subject matter related to the following copending applications:

Application Ser. No. 29/334,933, filed on even date herewith, entitled Front Portion of a Vehicle, Toy, or Likeness Thereof; and

Application Ser. No. 29/334,934, filed on even date herewith, entitled Rear Portion of a Vehicle, Toy, or Likeness Thereof.

FIG. 1 is a left, front perspective view of a vehicle, toy replica and/or other replicas according to our novel design, the right, front perspective view being mirror symmetrical;

FIG. 2 is a left, rear perspective view thereof, the right, rear perspective view being mirror symmetrical;

FIG. 3 is a left side view thereof, the right side view being mirror symmetrical;

FIG. 4 is a front view thereof;

FIG. 5 is a rear view thereof; and,

FIG. 6 is a top view thereof.

The broken lines are for illustrative purposes only and form no part of the claimed design.
